UNITED STATES PATENT OFFICE.

WILLIS A. GLOVER AND WILLIAM B. SMITH, OF TECUMSEH, ALABAMA.

HARNESS-SADDLE.

SPECIFICATION forming part of Letters Patent No. 236,944, dated January 25, 1881.

Application filed December 1, 1880. (No model.)

To all whom it may concern:

Be it known that we, WILLIS A. GLOVER and WILLIAM B. SMITH, citizens of the United States, residing at Tecumseh, in the county 5 of Cherokee and State of Alabama, have invented certain new and useful improvements in Harness-Saddles; and we do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 The present invention relates to that class of harness-saddles in which rigid non-absorbent pads are secured to adjustable bridge-pieces on an arched frame so that the saddle can be properly adjusted to suit the horse's back.

The invention consists in the construction and combination of parts which will be hereinafter more fully described and then set forth in the claims.

25 In the drawings, Figure 1 is a perspective view of a harness-saddle constructed according to our invention. Fig. 2 is a sectional view of one of the rigid non-absorbent pads.

The arched metallic frame which extends 30 over the back of the horse is composed of two curved side bars, B, which are each made of two parts pivoted or hinged together at the apex or top of the arch.

The hinge or pivot connection of the side-bars is effected by overlapping the contiguous 35 ends thereof and passing a pintle or stay-rod, C, through the same, this pintle, after passing through side bars, being properly riveted or otherwise secured in place.

40 Horizontal bottom flanges, D, formed on the outer sides of the side bars serve as a means for attaching the rigid pads E to the arched frame, the pads being screwed to them. The pads are generally made oblong in shape

45 and are constructed of a zinc or other metallic shell, G, struck up from a single piece of metal and adapted to receive a wooden filling or back piece, H. This filling or back piece is made solid to fill the entire shell of the pad 50 and give the necessary rigidity and strength to the same. The wooden filling or back piece

is secured to the metallic shell by turning the edges of the latter over said filling, as is clearly shown in Fig. 2. Pads constructed in this manner are light and strong, and are susceptible of being easily attached to the arched frame and detached therefrom when desired. 55

The pintle or stay-rod C at the apex of the arched frame carries a loose anti-friction or guide-roller, I, over which and a pair of similar rollers, J, located at the base of the frame, passes the customary back band or chain of the harness. The bottom guide-rollers are loosely fitted on transverse rods K, extending through the side bars of the frame, and these 60 rods also hold in position a pair of angle-irons or metallic plates, L, which partly extend over the rollers and prevent the back-band from slipping off, the back-band passing between the angle-plates and rollers. 65

The hinge connection of the arched frame permits the same to be properly adjusted so as to adapt the saddle to the horse's back. 70

For the purpose of obtaining a wider range of adjustment by more simple devices than 75 have hitherto been used in connection with adjustable pad-frames, we provide a curved or bow-shaped fastening rod or piece, M, one end of which has an inwardly-turned pin, N, which is received by one of a series of holes, 80 O, made in one of the side bars. The other end of the bow-shaped piece M is provided with a horizontal screw-threaded shank, P, which extends through one of a series of holes, Q, formed in the other side bar, and has a 85 winged screw-nut, R, applied thereto. By means of these holes in the side bars and the bow-shaped piece we are enabled to spread or contract the frame by simply shifting the pin N from one hole to another. 90

A harness-saddle constructed according to the present invention is particularly adapted for supporting the back-band of a plow-harness, as it will permit said back-band to work freely over the guide or anti-friction rollers, 95 thus always keeping the traces even and equalizing the draft on either side of the horse's shoulders.

Having thus described our invention, what we claim as new, and desire to secure by Letters Patent, is—

1. The combination of the bow-shaped fast-

ening piece or rod M, having inwardly-turned ends and a screw-nut, with the pivoted or jointed pad-carrying frame having a series of holes, as and for the purpose set forth.

5. 2. A harness saddle-pad composed of a metallic shell and a wooden filling or back-piece secured thereto by turning the edges of the shell upon it, as and for the purpose set forth.

3. The arched or curved bars constructed
10 with bottom flanges screwed to the pads, in

combination with the transverse pads having wooden backs, as and for the purpose set forth.

In testimony whereof we affix our signatures in presence of two witnesses.

W. A. GLOVER.

W. B. SMITH.
